Primary Examiner — Barbara Fox(74) *Attorney, Agent, or Firm* — Harness, Dickey & Pierce, P.L.C.(57) **CLAIM**

The ornamental design for an electronic device, as shown and described.

DESCRIPTION

FIG. 1 is a front perspective view of an electronic device showing our new design;

FIG. 2 is the front view thereof;

FIG. 3 is the rear view thereof;

FIG. 4 is the left-side view thereof;

FIG. 5 is the right-side view thereof;

FIG. 6 is the top-side plan view thereof; and,

FIG. 7 is the bottom-side plan view thereof.

The broken lines shown in the drawings illustrate portions of the electronic device that form no part of the claimed design.
